UNITED STATES PATENT OFFICE.

HAROLD E. NOCK, OF NEWBURYPORT, MASSACHUSETTS, ASSIGNOR TO TOWLE MANUFACTURING COMPANY, OF NEWBURYPORT, MASSACHUSETTS, A CORPORATION OF MASSACHUSETTS.

DESIGN FOR A BOWL OR ANALOGOUS ARTICLE.

Application filed February 13, 1923. Serial No. 5,162. Term of patent 7 years.

To all whom it may concern:

Be it known that I, HAROLD E. NOCK, a citizen of the United States, residing at Newburyport, in the county of Essex and State of Massachusetts, have invented a new, original, and ornamental Design for a Bowl or Analogous Article, of which the following is a specification, reference being had to the accompanying drawings, forming a part thereof.

In the drawings Figure 1 is a plan view of a bowl illustrating my new design; Fig. 2 is a view, in side elevation, of the bowl shown in Fig. 1; and Fig. 3 is a sectional view, in plan, taken on the line C—C of Fig. 2 and showing one-half of the bowl

configuration on this plane it being understood from Fig. 1 that the bowl is symmetrical.

The dominant feature of the design comprises the ornamental marginal decoration, a section only of which is shown in Figure 1 of the drawing.

It will be understood that the ornamental marginal decoration is continuous throughout the circumference of the bowl.

I claim:

The ornamental design for a bowl or analogous article, substantially as shown and described.

HAROLD E. NOCK.
